[57] CLAIM

The ornamental design for a notice assembly with rotatable message display, as shown and described.

DESCRIPTION

FIG. 1 is a top, left, front isometric view of a first embodiment of a notice assembly with rotatable message display showing our new design;

FIG. 2 is a front elevational view thereof;

FIG. 3 is a rear elevational view thereof;

FIG. 4 is a left side elevational view thereof, the right side elevational view being the mirror image thereof;

FIG. 5 is a top plan view thereof;

FIG. 6 is a bottom plan view thereof;

FIG. 7 is a top, left, front isometric view of a second embodiment of a notice assembly with rotatable message display showing our new design;

FIG. 8 is a front elevational view of the embodiment of the notice assembly with rotatable message display shown in FIG. 7;

FIG. 9 is a rear elevational view of the notice assembly with rotatable message display shown in FIG. 7;

FIG. 10 is a left side elevational view of the notice assembly with rotatable message display shown in FIG. 7, the right side elevational view being the mirror image thereof;

FIG. 11 is a top plan view of the notice assembly with rotatable message display shown in FIG. 7; and,

FIG. 12 is a bottom plan view of the notice assembly with rotatable message display shown in FIG. 7.
